(57)

CLAIM

The ornamental design for a pipetting tip, as shown and described.

DESCRIPTION

FIG. 1 is a perspective view of a pipetting tip showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.

The broken lines depict portions of the pipetting tip that form no part of the claimed design.

The dot-dash broken lines depict the boundaries of the claim and form no part thereof.
